Inventor,

J. S. SILLS
Derby, Mass.
Attorney,

United States Patent Office.

J. S. SILLS, OF CEDARVILLE, ILLINOIS.

Letters Patent No. 63,758, dated April 9, 1867.

IMPROVED WASHING MACHINE.

The Schedule referred to in these Letters Patent and making part of the same.

TO ALL WHOM IT MAY CONCERN:

Be it known that I, J. S. SILLS, of Cedarville, in the county of Stephenson, and State of Illinois, have invented a new and useful improvement in Washing Machine; and I do hereby declare that the following is a full, clear, and exact description thereof, which will enable others skilled in the art to make and use the same, reference being had to the accompanying drawings, forming part of this specification, in which—

Figure 1 is a top view of a wash-tub with my improved washer attached.

Figure 2 is a vertical section of the same, taken through the line *x x*, fig. 1.

Figure 3 is an under side view of the upper rubber.

Figure 4 is a top view of the lower rubber.

Similar letters of reference indicate like parts.

My invention has for its object to furnish a convenient and cheap apparatus which may be readily attached to a wash-tub, and easily removed, so that the tub can be used for other purposes if desired; and it consists in the lower rubber to be attached to the bottom of a wash-tub, formed by securing the ends of a series of parallel slots having their upper sides or edges rounded off to two semicircular pieces in the upper rubber, formed by attaching a series of parallel slats, having their upper edges or sides rounded off to a circular board, to the edge of which is attached a rim projecting downwards so as to be flush or nearly so with the lower edges of the said slats, as hereinafter more fully described.

A are the semicircular pieces, the edges of which are so formed as to fit the lower part of the tub, as shown in fig. 1. *B* are slats, the ends of which are securely attached to the pieces *A*. The slats *B* are placed parallel to each other, and their ends are of such a length as to coincide with the circular edges of the pieces *A*, as shown in fig. 4. The upper sides of the slats *B* are rounded off, as shown in fig. 2, so as to present a smooth surface to the clothes being washed. The lower rubber, when required for use, is secured to the bottom of the tub by screws *C* passing through the pieces *A* and screwing into the bottom of the tub, as shown in fig. 2. *D* are the slats of the upper rubber, which are secured to the lower side of the circular board *E* by screws or nails, or in any other convenient manner. The lower sides or edges of the slats or ridges *D* are rounded off, as shown in fig. 2, so as to present a smooth surface to the clothes being washed. *F* are two handles, which are attached to the upper side of the board *F*, one on each side, as shown in fig. 1. *G* is a rim, attached to the edge of the circular board *E* and projecting downward to or nearly to the lower edges of the slats or ridges *D*, to prevent the water from spattering while the machine is being used. *H* are small blocks, attached to the under side of the circular board *E* to support the rim *G* where it is unsupported by the ends of the slats *D*, as shown in fig. 3. *I* is a corrugated plate or ordinary rubbing-board, attached to the central part of the upper side of the circular board *E*, and secured in place by the cleats *J*, as shown in fig. 1. In using the machine the lower rubber is placed upon the bottom of a wash-tub and secured in place by the screws *C*. The water and clothes are then put in and the upper rubber placed upon them and operated by means of the handles *F* by turning it to the right and left with a rocking movement.

Having thus described my invention, what I claim as new, and desire to secure by Letters Patent, is—

The corrugated board *I* in combination with the upper rubbing-board *E*, having the slats *D*, rim *G*, handles *F*, the lower rubbing-board, consisting of the semicircular boards *A* and slats *B*, substantially as herein set forth for the purpose specified.

J. S. SILLS.
